UNITED STATES PATENT OFFICE.

SAMUEL BENJAMIN SHAPIRO, OF NEWBURGH, NEW YORK.

PROTECTIVE SWITCH FOR ELECTRIC FLAT-IRONS.

1,280,564.

Specification of Letters Patent. Patented Oct. 1, 1918.

Application filed September 11, 1917. Serial No. 190,840.

To all whom it may concern:

Be it known that I, SAMUEL BENJAMIN SHAPIRO, a citizen of the United States, residing at Newburgh, in the county of Orange and State of New York, have invented new and useful Improvements in Protective Switches for Electric Flat-Irons, of which the following is a specification.

This invention relates to improvements in protective devices for electric flat irons and the like.

In the use of electric flat irons it frequently occurs that the operator fails to turn off the current when the iron is not in use, thereby causing wastage of energy, and possibly burning out the heating unit of the iron or setting fire to adjacent objects. It is the purpose of the present invention to furnish an automatic switch which will cut off the current when the handle of the iron or other device is released by the operator.

Another object is to provide a switch of such construction that sparks or heated particles of metal which may fall from the contact points will be effectually confined within the switch-cavity.

An improved construction by which the manufacture of the switch is simplified, the durability increased, and the practical utility of the device amplified, constitutes a further object of the invention.

One form of the invention is described in the specification below, and illustrated in the accompanying drawings.

In the drawings:—

Fig. 1 represents a vertical longitudinal section through an electric flat iron handle constructed in accordance with the present invention.

Fig. 2 shows a transverse section through the handle on the line 2—2 of Fig. 1.

Fig. 3 is a detailed perspective view of the switch housing.

In the drawings the handle 1 of a flat iron is shown as secured to the usual connecting-members 2 extending downwardly for attachment to the iron proper. The handle 1 is formed in one side intermediately of its ends with a recess 3 of suitable shape and dimensions for containing the switch comprised in the present invention. The switch has a housing 5 formed in the outer side with a longitudinal slot 6, and is preferably rectangular in cross-section. Projecting lugs 7 on the housing are formed with openings 8 for passage of securing means shown

as screws 9 for securing the housing in the recess 3. A spring contact 10 is mounted on the inner wall of the housing and is adapted for establishing connection with a similarly located contact 11 when pressed up. As here shown, the spring 10 consists of a single piece of metal, but it is to be understood that it may be laminated or built up of a number of thin pieces when desired. Preferably, the housing is of insulating heat-resistant material such as fiber, but it may obviously be of metal, in which case suitable insulation is provided for each contact. Conductors 12 are attached to the contacts and connected in circuit with the heating unit of the iron so that the flow of current through the latter will be interrupted when the contacts are separated. As here shown a portion of each contact is prolonged through a suitable opening in the housing into a passage 14 through which the conductors 12 are led. The portions of the contacts which engage against each other may be tipped with platinum or similar non-corrosive metal.

For causing the contacts to establish connection when the handle is grasped, an elongated element 15 is movably mounted in and projects a suitable distance from the slot 6, and has flanges 16 and 17 overlying respectively the inner and outer portions of the housing adjacent the slot, and limiting the movement of the element 15. The portion of the element comprising the flanges 17 may be separately formed and secured to the main portion by screws 20. In order to prevent escape of sparks or hot particles of metal from the cavity of the housing, the element 15 is closely fitted to the slot, and it abuts against the end walls of the recess 3, while the flange 16 extends in proximity to the vertical walls of the housing adjacent the slot, or those walls perpendicular to that in which the slot is located. For the same purpose, the flange 17 overlies the handle at either end of the recess 3. Suitable compression springs 18 may be properly mounted within and attached to the housing, bearing against the element 15 to maintain it in the outward position when the iron is not in use.

It will be understood that the openings 8 are so located as to permit ready access to the screws 9. By removing the latter and withdrawing the housing somewhat from the recess 3 the element 15 may be instantly

removed by a longitudinal sliding movement to permit access to the interior of the switch. It will be noted that by the peculiar construction provided, the interior of the switch 5 is very effectively sealed to prevent escape of sparks, while the simplicity of the structure is calculated to reduce manufacturing costs and add to the reliability of the device.

While the form of the invention shown 10 and described is considered preferable, it is not to be interpreted as limiting the invention, as the right is reserved to variation within the scope of the claims. The invention is obviously not limited in application 15 to electric irons, but has a field of usefulness covering numerous branches of the electric art.

What is claimed is:— :

1. In a switch for electric devices, a housing 20 comprising a tube of rectangular cross-section formed in one side with a longitudinal slot, contacts within said housing, an elongated element mounted in said slot for movement to close said contacts, inner flanges 25 on said element overlying the portions of the housing adjacent the slot and extending in proximity to the adjacent vertical walls of the housing, and outer flanges on said element overlying the portions of the housing 30 adjacent the slot.

2. In a switch for electric devices, a handle 35 formed in the side with a recess, a tubular housing seated in said recess, said housing formed with a longitudinal slot, means for detachably securing said housing in the

recess, contacts within said housing, an elongated element mounted in said slot for movement to close said contacts, and flanges on said element overlying the portions of said housing adjacent said slot and limiting the 40 inward and outward movement of said element, the ends of said element adapted for abutting against the end walls of the recess whereby longitudinal displacement of said element is prevented when the housing is in 45 position in the recess.

3. In a switch for electric devices, a handle formed in the side with a recess, a tubular housing of rectangular cross section seated in said recess, said housing formed with 50 a longitudinal slot, means for detachably securing said housing in the recess, contacts within said housing, an elongated element mounted in said slot for movement to close 55 said contacts, inner flanges on said element overlying the portions of the housing adjacent the slot and extending in proximity to the adjacent vertical walls of the housing, outer flanges on said element overlying the portions of said housing adjacent the slot, 60 and extensions of the outer flanges overlying the handle adjacent the ends of the recess, the ends of said element adapted for abutting against the end walls of the recess whereby longitudinal displacement of said 65 element is prevented when the housing is in position in the recess.

In testimony whereof I affix my signature.

SAMUEL BENJAMIN SHAPIRO.
